UNITED STATES PATENT OFFICE.

WILLIAM J. DEMMING, OF CLEVELAND, OHIO, ASSIGNOR TO THE AMERICAN MULTIGRAPH COMPANY, OF CLEVELAND, OHIO, A CORPORATION OF OHIO.

HOLDER FOR PRINTING STRIPS AND METHOD OF MAKING THE SAME.

Application filed April 18, 1921. Serial No. 462,173.

To all whom it may concern:

Be it known that I, WILLIAM JOHN DEMMING, a citizen of the United States, residing at Cleveland, in the county of Cuyahoga and State of Ohio, have invented a certain new and useful Improvement in Holders for Printing Strips and Methods of Making the Same, of which the following is a full, clear, and exact description, reference being had 10 to the accompanying drawings.

This invention relates to assembled printing forms wherein the printing members comprise separate elements adapted to be secured upon a holder, and the invention is 15 concerned particularly with a very simple and satisfactory holder for printing members which are in the form of strips having inwardly flanged edges.

My invention is in the nature of an improvement in plate holders of the kind 20 shown in the application filed by Clifton Chisholm, Serial No. 462,250 filed April 18, 1921. In this Chisholm application, members struck from the body of the holder 25 serve to hold the character printing strip in position, and it is to an improved form of strip holding means that this application is directed.

One of the specific objects of my invention 30 is to provide strip holding means in the form of overhanging members integral with the plate, which members are of such form and made in such manner that the plate holder will not be weakened appreciably thereby, while the members will be 35 very effective in service and not liable to become displaced or distorted by rough handling.

Further objects of the invention will be 40 apparent from the following description taken in connection with the accompanying drawings, wherein Fig. 1 indicates the plan of a plate holder constructed according to my invention; Figs. 2 and 3 represent respectively end and side elevations of the 45 plate holder; Fig. 4 is a view similar to Fig. 1 showing the impression strips in position; Fig. 5 is a section on the line 5—5, Fig. 4; Fig. 6 is a section on line 6—6, Fig. 50 4; Fig. 7 is a section on line 7—7, Fig. 4; Fig. 8 is a section on line 8—8, Fig. 4; and Fig. 9 is a section on line 9—9, Fig. 4.

Referring to the drawings by reference

characters, the plate holder indicated at 10 comprises a body portion 11 having end 55 rails 12—12 thereon. These end rails may comprises portions of the metal folded or rolled to position.

A portion of the plate holder beneath each rail is indented as at 14 to allow wheels 60 on inking rollers to bring the latter to inking position. The top of the plate is shown as cut away at 15 and as provided with a folded-over portion 16, adapted to coact with struck up prongs 17, to secure an 65 identification card 18 in place. Suitable means to prevent lateral displacement of this identification card may be provided which I have shown as struck-up portions 19 and 20. The lower portion of the plate may be 70 folded over, as shown at 21 to afford a reinforcing rib.

The plate holder is adapted to be used in connection with detachable impression members. To enable such impression members to be secured in position, I have shown 75 means comprising a number of parallel rows of bosses 40. These bosses each comprise a central portion 41, which is shown as substantially flat and parallel with the body 80 portion of the plate from which it may be struck.

This central portion is separated from the body of the plate along curved lines 42 and 43, and is joined at each end to the 85 plate by webs or tongues 44. These webs 44 are of less width than the flat portion 41, so that the latter project beyond the line of the webs on either side to afford projections or shoulders 46, best shown in Fig. 7. 90

It will thus be seen that each row of bosses 40 provides in effect a continuous line of members, T-shaped in elevation, rising above the plane of the plate holder. The plate holder thus produced is much stronger than 95 others wherein the holding tongues are separated from the body of the plate along three lines.

The impression member is shown as comprising a substantially flat strip 50 having 100 suitable printing characters 51 thereon. The lateral edges of the strip are bent as at 52 to form holding flanges. These flanges are adapted to engage the sides and beneath the projections 40, to thereby hold the impression strips in place.

The printing strip may be made to fit the projections tight enough to prevent accidental displacement.

In use, a properly lettered printing strip 5 is fitted over an end projection, and the strip is moved to proper position. I have shown the holder as adapted to receive five strips although more or less, as desired, may be used.

10 Having thus described my invention, I claim:

1. A printing strip holder having a row of bosses thereon connected with the holder at two opposite sides, and disconnected 15 therefrom at its other two sides to provide overhanging portions, and a printing strip adapted to overlie said bosses and having inwardly flanged edges adapted to extend beneath said overhanging portions.

20 2. A plate having a boss pressed therefrom, and connected with the plate at two opposite sides, and disconnected from the plate at its other two sides to provide overhanging portions, and a printing strip adapted 25 to overlie said boss and having inwardly flanged edges adapted to extend beneath said overhanging portions.

3. A holder having a row of bosses thereon connected with the holder at two opposite 30 sides, and disconnected from the holder at its other two sides to provide overhanging portions.

4. A plate having a line of bosses struck therefrom, said bosses being connected with 35 the plate in line with the row and being disconnected with the plate transverse of the row.

5. A plate having a plurality of bosses struck therefrom and disposed above the 40 plane of the plate, the bosses being connected with the plate at two spaced sides and having the portion intermediate the points of connection overhanging the plate.

6. A holder having a plurality of oppositely facing, directly connected, struck-up 45 projections thereon, and a trough shaped impression member secured over and beneath said projections.

7. A printing strip holder having a plurality of oppositely disposed retaining projections thereon, the material intermediate the projections being continuous in a straight line throughout the length of the plate 50 holder.

55 8. A holder formed from sheet metal comprising a body portion having a plurality of oppositely disposed projections thereon, said projections having the same thickness as the body portion and being connected to 60 the body portion along two sides and disconnected from the body portion along two curved lines.

9. The combination of a printing strip 65 holder having a body part with a series of engaging members thereon, each member in-

cluding a central part and two oppositely disposed engaging portions, and a printing strip adapted to overlie the central part and having parts adapted to extend beneath the engaging portions.

10. A holder comprising a sheet metal body portion having a plurality of directly connected projections thereon, said projections being parallel to the body of the plate holder, and the projections and their connecting portion being pressed therefrom, and an impression member secured by said projections.

11. A printing strip holder having pairs of oppositely facing projections thereon, 80 said projections being arranged above the body of the holder, each pair of projections being united by a web parallel to the holder but spaced from it, said web being connected at opposite edges intermediate the 85 projections with the holder.

12. In a holder, a body part having a series of engaging bosses thereon, each boss including a central portion and two engaging 90 projections, said central portion being joined to the holder by webs.

13. In a holder, a sheet metal plate having a series of engaging bosses pressed therefrom, each boss including a central portion and two engaging projections, said central portion being joined at its opposite edges 95 to the holder.

14. In a printing strip holder, a plurality of retaining projections thereon, said projections being defined by material struck 100 from the body of the holder, and being oppositely disposed and having their roots directly connected.

15. A holder having impression strip retaining means thereon, said retaining means 105 comprising a portion including a plurality of pairs of projections separated from each other and from the plate holder along two oppositely disposed arcuate curves, said portion defined by the curves being disposed 110 above the plane of the plate holder.

16. A sheet metal holder having impression-member-engaging means, said means comprising bosses disconnected from the plate holder along two sides and disposed 115 above the plane of the plate holder and having oppositely directed projections thereon.

17. A sheet metal holder having pairs of projections thereon, the projections in each pair facing in opposite directions and disconnected from the holder on two sides and arranged above the body of the holder, said projections being joined by a web, and an impression member resting upon said web and having portions extending beneath said 125 projections.

18. In a printing strip holder made from sheet metal, a body part having a series of engaging members thereon, each member including a central portion disconnected from 130

the holder on two sides and two engaging portions, said central portion being joined to the holder by webs of less width than said engaging members.

5 19. A printing strip holder having a row of bosses pressed therefrom, said bosses being connected with the holder only by two necks which are narrower than the head of the boss and are located respectively at the 10 opposite edges of the boss and extend in the direction of the row.

20. A printing strip holder having parallel rows of bosses pressed therefrom, each boss having a head above the body of the 15 holder and two narrower necks connecting opposite edges of the head with the holder and extending in the direction of the row.

21. A printing strip holder having a row of bosses pressed therefrom, each boss having a substantially circular head and two necks narrower than the head and connecting its opposite edges with the holder in the direction of the row, the remaining arcuate edges of the head being free.

25 22. The method of providing a printing strip holder with gripping projections comprising slitting the body portion of the holder along opposed disconnected lines concaved toward each other and raising the material, between the slits, above the plane of the body portion.

23. The method of providing a printing strip holder with gripping projections comprising slitting the body portion of the 35 holder along opposed disconnected lines and raising the material between the slits, above the plane of the body portion while leaving

it connected with the body portion by two comparatively narrow necks.

24. The method of providing a holder 40 with gripping projections comprising slitting the body portion of the plate holder along opposed curved lines and simultaneously raising the material between the slits, above the plane of the body portion while 45 leaving the material at the ends of the slits connected with the body portion.

25. The method of providing a plate with a row of retaining projections comprising pressing the projections from the plate, disconnecting two of their edges therefrom along lines which approach the axis of the 50 row, while leaving the projections connected with the plate by necks extending in the direction of the row.

26. The step in the method of making holders for printing strips, which comprises pressing a boss from a plate to form a head disconnected from the plate at two edges while leaving two necks narrower than the 60 head connecting opposite edges of it with the plate.

27. The method of providing a holder with gripping projections comprising shearing the body portion of the holder along 65 opposed spaced lines which approach each other at their ends and simultaneously raising the material between such lines above the plane of the body portion without shearing the material at the ends of the varied 70 projections.

In testimony whereof, I hereunto affix my signature.

WILLIAM J. DEMMING.
